UNITED STATES PATENT OFFICE.

ALMER McDUFFIE McAFFEE, OF BAYONNE, NEW JERSEY.

PROCESS OF IMPROVING OILS.

1,127,465.

Specification of Letters Patent.

Patented Feb. 9, 1915.

Application filed February 12, 1914. Serial No. 818,286.

To all whom it may concern:

Be it known that I, ALMER McDUFFIE McAFFEE, a citizen of the United States, residing at Bayonne, in the county of Hudson and State of New Jersey, have invented certain new and useful Improvements in Processes of Improving Oils, of which the following is a specification.

This invention relates to processes of improving oils; and it comprises a method of treating petroleum oils to secure greater quantities of distillates of better quality than are given by the usual practice and to secure a better quality of residual oil; and, more specifically stated, it comprises a process wherein petroleum oils are heated in the presence of aluminum chlorid in such a manner as to secure a catalytic conversion of a portion of the higher boiling oils into lower boiling oils, such lower boiling oils being distilled off and removed, and to convert the residual oil into a better grade of material than is obtained by present processes; such process being particularly applicable to the improvement of crude petroleum; all as more fully hereinafter set forth and as claimed.

The crude petroleums from the various oil-producing districts differ materially in quality and constitution. Some of these oils, like Pennsylvania oil and Caddo (Louisiana) oil, are largely of a paraffin nature; that is, they are neutral bodies which do not oxidize readily, are clean smelling and require but little acid in refining. Others of these oils, like Mexican crude and some of the Texas crudes, contain large amounts of asphaltic bodies, and their distillation products are not of high grade, tending to oxidize and gum on exposure to air. Other oils, like certain Oklahoma crudes, are of an intermediate nature containing both paraffin and asphalt. Many of these oils, like the Texas and Mexican crudes, contain large amounts of sulfur. Mexican crude also contains organic nitrogen.

In the ordinary process of distilling any of these crudes the gasolene (if any be present) and the kerosene (if any be present) naturally contained therein are first distilled off. The residual oil, remaining in the still after the naturally occurring gasolene and kerosene have been removed, is worked up into a variety of products, depending upon the character of the particular crudes and upon market conditions. In

some cases with some of these crudes, the whole of this residual oil is marketed as fuel oil, no attempt being made to utilize it for higher grade products. In other cases the residual oil is itself distilled further to produce lubricating stocks and cylinder oils in fire-heated stills with the aid of steam introduced into the oil body; by what is usually termed "bottom steam" distillation. Except in the case of asphaltic oils, if the residual oils contain substantial amounts of paraffin, they may be subjected to the so-called cracking process whereby the paraffin is caused to become crystalline, which is generally necessary in separation of paraffin wax from oil by pressing. A relatively small amount of gasolene and burning oils is produced and recovered from high boiling hydrocarbons during this cracking operation, but the quality of these products is poor on account of their highly unsaturated nature, and the lubricating values of the paraffin oils are considerably impaired.

With all these oils, the residual materials after distilling off the naturally occurring gasolenes, or gasolene and burning oils, are susceptible of improvement by the process hereinafter set forth. While the residues from Pennsylvania and Caddo crudes, and similar crudes, are of high grade, as oils run, the residues from many of the other oils are of low grade and some are so low grade as to be useful only as fuel. It is one purpose of this invention to improve these high-boiling oils; and in the case of asphaltic oils or oils containing both asphaltic and paraffin constituents the improvement goes so far as to convert what would otherwise be practically worthless material, except as fuel, into valuable material. But even with high grade crudes, like Pennsylvania and Caddo oils, I obtain a substantial improvement.

In my process, I heat these crude oils with aluminum chlorid to improve their character; and by a proper use of this chemical I find I can not only obtain high-boiling oils of much better quality but also obtain a large yield of what I may term, for the sake of a name, secondary distillates of high grade. The action of the aluminum chlorid is, in part, to produce or form low-boiling bodies like gasolene; and by proper manipulation in the present process I can form a secondary distillate of gasolene or of gasolene, solvent oils (commercially often called "turpentine substitutes") and kerosene.

Such a secondary distillate is water white, sweet, and substantially saturated, and is not like the cracked gasolenes or cracked distillates frequently made by destructively distilling residual high boiling oils after removal of the primary distillate of naturally contained gasoline, or gasoline, solvent oils and burning oils. And this secondary distillate consisting of high grade gasoline I 10 can produce from oils which naturally contain no gasoline; that is oils which do not yield a primary gasoline upon simple distillation. For example, on heating a low grade asphaltic crude, like Sour Lake 15 (Texas) crude containing no primary or natural gasoline with aluminum chlorid, I secure a good yield of high-grade gasoline and burning oils, while from the high-boiling residual materials, I may obtain pale 20 lubricating oils and cylinder oil, both free of asphaltic constituents.

Many crude oils which normally cannot be used to produce paraffin (like some Oklahoma crudes) can be transformed into oils 25 useful for this purpose. Some Oklahoma crudes contain both paraffin and asphalt but owing to the presence of the latter the former cannot be obtained by the usual methods. On treatment with aluminum 30 chlorid, the asphalt and asphalt yielding hydrocarbons of the oil are converted into other bodies, probably, to a large extent at least, by conversion into lighter oils, and the oil under treatment loses much of its viscosity. From the oil so treated it is practicable to produce paraffin. Crude oils containing sulfur and nitrogen may be freed of these elements by aluminum chlorid. With 35 a little aluminum chlorid, I can convert Mexican crude into a fuel oil low in sulfur and meeting exacting specifications in this respect as well as in regard to viscosity.

In all cases prior to using aluminum chlorid I first heat the oil to dry it and, in 45 case gasoline is naturally contained, to recover it as a primary distillate. I then add my aluminum chlorid in such quantity as may seem expedient with the particular oil used and for the purpose intended and heat 50 for a time long enough to convert the unsaturated bodies into saturated and to cause asphaltic bodies to disappear. This causes also the formation of a relatively large amount of secondary gasoline of high 55 grade, and this I generally remove and recover. Often, since I am here seeking to purify and stabilize heavy oils I adjust heating conditions, time of treatment, quantity of aluminum chlorid, etc., so as to leave 60 about 30 to 50 per cent. of oil (calculated on the amount of crude oil used) in the still when the removal of newly formed light oils is completed; but this proportion may vary. But generally there is at least a substantial 65 quantity of heavy oil remaining. This I

may remove from the still and treat with sulfuric acid prior to performing the usual operations for the manufacture of lubricating oil and wax-bearing distillate, or cylinder oil, as the case may be. The sulfuric 70 acid treatment is more for the purpose of removing traces of aluminum chlorid than for the ordinary purpose of removing unsaturated bodies. I may use a half or third the quantity of acid ordinarily employed in treating oils. Of course other ways of removing residual aluminum chlorid may be employed, such as steaming or moistening, but a sulfuric acid treatment is simple and satisfactory. Most of the aluminum chlorid does not remain in the oil but separates out when the oil cools as a sludge of coky residue from which the aluminum chlorid may be regenerated. 75 80

Petroleum oils when heated with aluminum chlorid undergo profound internal changes; and these changes are utilized in the present invention. In a general way, it may be said that there appears to be a tendency for a rearrangement of the various 90 groups constituting the hydrocarbon molecules with conversion of unstable into chemically stable bodies. In this rearrangement there is usually, at high temperatures, a formation of secondary low-boiling oils and 95 these are of course worth recovering. In the present invention I do not carry the conversion so far as to convert all, or substantially all, of my oil into gasoline and the like but conduct the operation in such a 100 way as to leave a substantial proportion of high-boiling oils, the amount remaining being often around 30 to 50 per cent.

While a treatment of oil with aluminum chlorid at high temperatures leads to the 105 production of low-boiling bodies at the expense of high-boiling, at low temperatures, say around 150 F., the conversion does not go so far; a fact which may be utilized in the purification and decolorizing of lubricating oils. Such oils in so treating while undergoing profound internal changes of beneficial character do not furnish any material amount of low boiling oils. In the present invention while I utilize the beneficial effect of aluminum chlorid upon the character of high boiling oils, I go somewhat further and by operating at higher 110 temperatures also produce a proportion of low-boiling as a by product oils. 115 120

As a rule, in producing my secondary volatile products, I prefer to make mainly gasoline, although this is a matter of market conditions, and I may at times produce gasoline, burning oils and the grade known 125 as solvents. While gasoline is always produced, the particular character of the secondary products made depends mainly upon the temperature at which such secondary products are allowed to escape from the 130

still. If the still be so arranged as to condense and return, or reflux, all products condensable at 300° F. the product will be mainly gasolene; where higher-boiling materials are allowed to go past the condenser, I may obtain much of the other volatile bodies.

The amount of aluminum chlorid employed depends upon the particular results sought. Where I wish mainly to improve the quality of the residual oil I need use only a small amount, say 1 to 3 per cent.; if I am seeking also a large production of gasolene, it is generally better to increase the proportion somewhat, say to 5 per cent. The aluminum chlorid employed may be made in any convenient way, as by treating aluminum, or alumina and carbon, with chlorin or hydrochloric acid. Aluminum chlorid may be recovered from the residues after treating oil by heating such residues to carbonize them and passing into contact therewith a small amount of chlorin or hydrochloric acid. Somewhat heightened results may be obtained by using in lieu of aluminum chlorid an addition of finely divided metallic aluminum to the oil, and passing chlorin into the oil. The proportions of aluminum chlorid stated are, however, only indicative; the amount employed must always vary with the particular oil and with the particular purpose for which my process is employed. It will also vary with the way in which the process is conducted. For example, instead of using about 5 per cent., which is generally a suitable quantity—I may add 10 per cent. of aluminum chlorid to a charge of oil and heat therewith until the delivery of gasolene beyond the condenser begins to diminish or, until the development of the gasolene vapors lessen. At this time, I may cool the oil to allow the aluminum chlorid to deposit, removing the cooled oil for further treatment elsewhere and then add another like charge of dry oil to the aluminum chlorid remaining in the still. Here although I have added 10 per cent. in the beginning I am virtually using only 5 per cent. for a single charge. The aluminum chlorid may of course be added portionwise; that is instead of adding 5 per cent. at once, this amount may be added in two or three or more portions. There is however little advantage in this.

The oil temperature in the operation is generally at the boiling point; around 500° F. Where I am making a large proportion of gasolene, the oil may be at any temperature from 500° to 600° F., but is generally around 500° F., while I hold the temperatures of the vapor allowed to leave the vapor line of the still at not above 300° to 350° F.

The time of treatment varies with the specific results sought. Ordinarily I heat

with the aluminum chlorid until it loses most of its activity and tends to settle out as a coky residue, or until, in the event I am making gasolene, the delivery of condensed gasolene from the condensers begins to dwindle. The time required ranges from 36 hours to 48.

As illustrative of a typical embodiment of my invention in actual practice, I may describe the treatment of a low grade asphaltic Texas crude oil. This was an oil of 155° F. flash point and containing no natural gasolene. A preliminary distillation of a sample showed an over-point (the temperature of the vapor at which distillation began) of 307° F. 10 per cent. distilling over below 481° and 44 per cent. below 600°, the temperature at which cracking began. A charge of the Texas crude was first heated in still to get rid of water. At the time when the temperature in the vapor line at the point of entrance to the condenser showed 350° F., I deemed the oil free of water. There was a distillate (3.57 per cent.) which was of the character of burning oil. I then added 5 per cent. by weight of aluminum chlorid (on the weight of oil remaining in the still) and continued the heating, adjusting conditions so that the vapor temperature at the point stated remained around 350°. There was a formation of secondary distillate and at the end of 48 hours the flow from the condenser slackened owing to the aluminum chlorid becoming less active. The secondary distillate obtained amounted to 48.81 per cent. of the original crude oil. With the apparatus and under the conditions which I used in this particular operation, I sent over into this distillate solvent oils and burning oils in addition to gasolene. I therefore redistilled in three cuts to separate these materials. I obtained (calculated on the original crude oil) 24.40 per cent. gasolene, 12.15 per cent. solvent oils and 12.26 per cent. burning oils. All were waterwhite, clean-smelling and required no acid or other purifying treatment to finish them for their respective uses.

Returning now to the residual oil remaining in the still at the end of the described distillation, this oil amounted to 33.33 per cent. of the original crude oil. It was cooled and drawn off, leaving a granular coky sludge containing aluminum chlorid. This sludge was then treated to regain adhering oil and recover aluminum chlorid. The withdrawn oil was treated with fuming sulfuric acid to remove any dissolved aluminum chlorid, using the acid in about the proportion of 12 pounds per barrel. The 33.33 per cent. residual oil after the acid treatment was a bright red oil, clean-smelling and free of asphaltic constituents. It had a flash point of 285°; a fire test of 360; and a viscosity

(Saybolt Universal viscosimeter) of 177 at 100° F. It was worked up into pale lubricating oils of excellent quality and cylinder stock. There was no tar. This crude oil is one which is not ordinarily employed for making burning oils. It contained no gasolene. The one low-boiling distillate usually made from it is solvent oil. To make this oil it is steam distilled with bottom steam 10 in the ordinary way. About 80 per cent. of oil remains in the still at the time when this solvent oil has gone over. The solvent oil, unlike the volatile oils obtained in the present invention from the same material, 15 required refining with acid. The 80 per cent. remaining in the still by the usual process is black, acrid-smelling and highly unsaturated. When the distillation is continued beyond this point there are produced 20 gas oil, lubricating stocks and residual tar from which asphalt is made. The gas oil is a relatively low priced material and the tar has little value. The lubricating stocks are of low grade and require a treatment 25 with at least 20 or 30 pounds of sulfuric acid per barrel, followed by an alkali wash and fullers' earth treatment to make them of a grade corresponding to that of similar material obtained by the present process. 30 In the operation described, in lieu of obtaining the tar which would be made in the ordinary practice I obtain cylinder oil of excellent quality; red in body and having a light green bloom. Tabulating the results 35 obtained on this oil, for a 1,000 barrel charge I obtain 35.7 barrels of primary distillate (kerosene); 244 barrels of gasolene; 121.5 barrels of solvent oils; 122.6 barrels of burning oils; 155 barrels solar oil; 62 barrels pale 40 lubricating oil; and 93 barrels of cylinder stock—all of high grade. The loss on this basis would be 166.2 barrels as gas, coke, and in acid treatment. 45 In treating a Mexican crude oil, containing both asphalt and paraffin, and containing sulfur in large amount together with nitrogen, I first distilled to remove water and a primary distillate. This primary distillate amounted to 10.72 per cent., mostly 50 gasolene. I then added 5 per cent. of aluminum chlorid and continued the heating. I now obtained 25 per cent. of secondary distillate half of which was gasolene. In spite of the low quality of the original crude 55 oil, the gasolene from this secondary distillate was clean smelling, water white and needed no treatment with acid. The residual high boiling oil after separating the aluminum chlorid amounted to 40 per cent. of the original crude. It was greenish and free 60 from asphaltic constituents. The flash point was 310° F. and the pour or cold test (the point at which the liquid becomes too viscous to pour) was 55° F. This residual oil I 65 worked up into wax stock and cylinder oil.

Both were of good quality in spite of the presence of asphalt and a large amount of sulfur in the original crude oil.

With a Caddo oil, which I treated to obtain a stock of the nature of that commercially known as vaseline stock, I first distilled to free it of water and obtained a primary distillate. The primary distillate amounted to 26.19 per cent. I then added 5 per cent. of aluminum chlorid and continued the heating. I now obtained 41.67 per cent. of secondary distillate, about half of which was gasolene. In this operation, I pushed the manufacture of secondary distillate to a point where I had left in the still 75 18.7 per cent. of residual oil. This residual oil after the aluminum chlorid had been separated, was a "light pale" oil of 260° F. flash and a pour test of 90° F. This material was worked up into vaseline by distilling with bottom steam until 30 per cent. of light lubricating oil had passed over. The residue was light-colored material which only needed filtration with fullers' earth to give a high grade vaseline-like product. I 80 obtained 13.1 per cent., calculated on the crude, of commercial vaseline. 85

With an Oklahoma crude containing both paraffin and asphalt which I treated to obtain a relatively large quantity of secondary 90 gasolene, I obtained 20.83 per cent. of primary distillate in heating till a thermometer in the vapor line recorded 350° F. Of this 14.58 per cent. (on the crude) was gasolene. On now adding 5 per cent. aluminum 100 chlorid, I obtained 50.60 per cent. of secondary distillate. In this operation I wished to make a large quantity of secondary distillate of gasolene and burning oils. On redistillation I obtained 21.50 per cent. (on the 105 crude) of high-grade gasolene. In the still at the time I discontinued distilling for secondary products, I left 14.07 per cent. (on the crude) residual oil. This, after treatment with sulfuric acid, had a pale 110 color with green bloom; a flash point of 300° F. and a pour test of 90° F. This material was worked up into wax stock and cylinder oil, the yield of the latter being 5.24 per cent. (on the crude), with a green color, 115 fire test of 615° F. and a pour test of 30° F. Although the crude oil contained asphalt, no tar was made and from the wax stock, treated in the usual ways, I secured good 120 white paraffin wax.

In the work recorded in the foregoing exemplificatory operations, I used conditions such as gave me burning oils and solvent oils as well as gasolene. In similar work however on the same oils where I desired to increase the amount of gasolene in the secondary distillate, I secured this result by simple refluxing back the burning oil and solvent oil fractions. 125

While the described process is not in any 130

way dependent on any particular type of apparatus, and indeed may be performed in any of the usual stills, I have shown more or less diagrammatically, an apparatus of a type I have used with advantage in the conversion of oils with production of secondary gasoline. In this showing the figure is a central vertical section (partly in elevation) of a single still and accessory parts.

10 Element 1 designates the still proper, as a whole. Oil may be introduced through a valved inlet 2 and withdrawn through a valved outlet 3. Firing means are diagrammatically shown at 4. At the top, the still 15 is provided with the top 5, carrying stirring means 6. In a small sized still the whole top may be removable. Passing through the cover is a vapor outlet 7 leading to the chamber 8. The vapor line 9 leads from this 20 chamber to an air cooled condensing chamber 10. As shown, this is of simple cylindrical design; but any other type of air cooled condenser may be substituted in its stead. From this condensing chamber a 25 vapor conduit 11 leads to another and similar condensing chamber 12. Beyond this chamber is a vapor conduit 13 carrying a thermometer 14 and provided with a valve 15. Beyond the valve this conduit connects 30 with a condenser or cooling device 16, shown diagrammatically as a series of connected pipes in a tank 17, adapted to hold water or other cooling fluid. At the base of the first air condensing chamber is an outlet 18 connected to a reflux conduit 19. As shown, 35 this reflux conduit has a portion 20 at a lower level to serve as an oil trap. Connected to this reflux conduit is an outlet 21 for the second air cooled condensing chamber. The valve 22 allows communication 40 between the outlet and the reflux conduit to be closed or opened at pleasure. Connected to element 21 above this valve is a valved outlet conduit 23 leading to a cooler 24 shown as located in the same cooling tank 45 as 16. The manhole 25 may be provided in the top of the still for introducing aluminum chlorid and for other purposes. In the use of this structure, a suitable charge 50 of crude oil may be introduced through the inlet 2 and heated until the thermometer 14 shows a vapor temperature between 300° F. and 350° F. At this time the oil is free of water. Aluminum chlorid in the desired 55 amount may now be introduced through the manhole 25 and the heating continued. An evolution of vapors of low boiling oils at once begins and passes upward past the chamber 8 through the conduit 9 into the 60 condenser 10. The chamber 8 serves to retain and return any aluminum compounds, etc., that may be carried up mechanically or otherwise. In the condensing chamber 10 vapors are more or less cooled and such oil 65 as condenses passes downward through 18

into 19, and back to the still, the depression 20 serving as an oil trap. Uncondensed vapors go forward through 11 into the conduit 12 where a further condensation takes place. The valve 23 being closed and the 70 valve 22 open, the condensate formed in this chamber returns or refluxes through the trap 20 and conduit 19 to the still. With the thermometer 14 standing at 300° F. to 350° F., vapors passing forward to and condensed in the condenser 16 will be mainly gasoline. This gasoline may be refractionated in any way and in any suitable apparatus. Where it is desired to make two such cuts in this distillation, the valve 22 may be closed and the valve 23 opened. In this event, high boiling oils condensing in the element 10 reflux back as before while such oils as condense in the chamber 12 instead of going back to the still pass beyond the 75 outlet 23 into the cooler 24. When making two cuts in this manner, the gasoline condensed in element 16 needs no further re-distillation. The product collected from the cooler 24 will be solvent and burning oils 80 or either according to the temperature in the condenser 12. 85

While for the sake of simplicity of illustration I have shown but two air-cooled condensers used in series and have shown means for collecting but two cuts and have shown these elements as of a simple type, it will be obvious that any number of condensers may be used in series and that they may be of any type. The condensers may be cooled in 90 any other way in lieu of being simply air cooled as shown. 95

In using the above described apparatus, after charging the oil, heat may be applied till the flow of condensate from condenser 16 slackens. Aluminum chlorid may be added in the desired amount and heating continued. A new flow begins and when this slackens, firing may be interrupted and the residual oil cooled and removed. 100

The expulsion of water and primary distillate may of course be effected in one still and the hot dry oil transferred to another still for treatment with aluminum chlorid if it is desired. 110

What I claim is:—

1. In the improvement of oils the process which comprises heating a high boiling oil with aluminum chlorid while distilling off low boiling oils formed, cooling the heated 120 oil at a time when a substantial amount of high boiling oil still remains and separating the aluminum chlorid from the high boiling oil.

2. In the improvement of crude petroleum, the process which comprises heating a crude petroleum to remove low boiling oils and moisture, adding aluminum chlorid, heating with removal of low boiling oils formed during such heating, cooling the 125 oil, 130

- petroleum at a time when a substantial amount of high boiling oil still remains and separating the aluminum chlorid and the high boiling oil.
5. 3. The process of improving crude asphaltic petroleum which comprises distilling the same with aluminum chlorid until a portion of the high boiling oils is converted into saturated compounds and freed of asphaltic constituents, said low boiling oils being removed as fast as formed and the heating operation being interrupted while a substantial portion of the high boiling oil so freed of asphalt still remains.
10. 4. In the improvement of crude petroleum, the process which comprises heating a crude petroleum to remove low boiling oils and moisture, adding aluminum chlorid and distilling off the low boiling oils produced thereby till a substantial proportion but not all of the high boiling oil has been converted into low boiling oils, cooling residual high boiling oil, and separating the high boiling oils and the aluminum chlorid.
15. 5. In the improvement of petroleum oils, the process which comprises heating such an oil to free it of moisture and low boiling oils, adding aluminum chlorid and heating to distil off low boiling oils formed, such heating being discontinued when an amount of oil at least 30 per cent. of the original oil still remains, cooling this remaining oil and separating oil and aluminum chlorid.
20. 6. In the improvement of crude petroleum the process which comprises freeing a crude petroleum of moisture and primary gasoline, adding aluminum chlorid and heating to form and remove secondary gasoline, cooling residual oil while a substantial amount still remains and separating oil and aluminum chlorid.
25. 7. In the manufacture of secondary gasoline by heating a body of high boiling oils with aluminum chlorid, the process of manufacturing high grade lubricating oils which comprises interrupting said heating while a substantial quantity of high boiling residual oil remains, cooling the residual oil and separating aluminum chlorid and refining the residual oil to produce high grade lubricants.
30. 8. In the improvement of petroleum oils, the process which comprises distilling such an oil with aluminum chlorid, cooling the residual oil and finally removing dissolved aluminum chlorid by treatment with sulfuric acid.
35. 9. In the improvement of petroleum oils, the process which comprises heating such an oil to a temperature below 600° F. in the presence of aluminum chlorid, interrupting the heating while a substantial quantity of liquid oil at this temperature
- still remains, cooling and finally removing dissolved aluminum chlorid by treatment with sulfuric acid.
10. In the improvement of petroleum oils, the process which comprises heating such an oil to a temperature below 600° F. in the presence of aluminum chlorid, interrupting the heating while a substantial quantity of liquid oil at this temperature still remains, cooling and separating oil and aluminum chlorid.
11. In the improvement of petroleum oils the process which comprises heating crude petroleum oil till the evolution of vapors substantially slackens, adding a relatively small amount of aluminum chlorid, heating till evolution of vapors slackens, cooling the oil and separating oil and aluminum chlorid.
12. In the improvement of crude petroleum oils the process which comprises adding one to five per cent. aluminum chlorid to such an oil, heating till formation of vapors of lower boiling products slackens substantially, cooling and separating oil and aluminum chlorid.
13. In the treatment of petroleum oils the process which comprises distilling off primary gasoline, adding aluminum chlorid, distilling off secondary gasoline, cooling residual oil and separating oil and aluminum chlorid.
14. In the treatment of petroleum oils the process which comprises heating such an oil with aluminum chlorid for 36 to 48 hours while removing vapors of secondary gasoline, cooling and separating oil and aluminum chlorid.
15. In the improvement of petroleum oils the process which comprises heating the same with aluminum chlorid while constantly removing vapors at a temperature not above 350° F., such heating being interrupted at a time when a substantial amount of high boiling oil still remains and such high boiling oil being cooled, and separating the aluminum chlorid and cooled oil.
16. In the improvement of petroleum oils the process which comprises heating such an oil with aluminum chlorid while removing vapors at a temperature not above 350° F., vapors condensing above this temperature being condensed and refluxed back, cooling the oil at a time when a substantial amount of high boiling oil still remains, and separating the oil and aluminum chlorid.
- In testimony whereof, I affix my signature in the presence of two subscribing witnesses.
- ALMER McDUFFIE McAFFEE.
- Witnesses:

JULIA M. McCABE.

It is hereby certified that in Letters Patent No. 1,127,465, granted February 9, 1915, upon the application of Almer McDuffie McAfee, of Bayonne, New Jersey, for an improvement in "Processes of Improving Oils," errors appear in the printed specification requiring correction as follows: Page 2, line 83, for the word "of" read *or*; same page, line 120, after the compound word "low-boiling" insert the word *oils* and same line after the word "product" strike out the word "oils"; page 3, line 42, for the word "lessen" read *lessens*; page 6, first-mentioned witness to the signature of the patentee, for "F. K. Hauxhurst" read *T. S. K. Hauxhurst*; and that the said Letters Patent should be read with these corrections therein that the same may conform to the record of the case in the Patent Office.

Signed and sealed this 13th day of April, A. D., 1915.

[SEAL.]

J. L. NEWTON,

Acting Commissioner of Patents.
